ATTACHMENT FOR THE INTAKE OF
INTERNAL-COMBUSTION ENGINES

George W. Miller, Salisbury, N. C.

Application October 20, 1952, Serial No. 315,612

14 Claims. (Cl. 123—119)

1

This invention relates to attachments for use with an internal combustion engine for facilitating the starting of the engine when it is hot. These attachments are particularly for use on the intake manifold and the air filter of the engine.

With some cars, when the intake manifold is very hot after the car has been running and the engine is stopped, it is difficult to start the engine again as long as it remains fairly hot, due to the fact that the mixture in the intake manifold and carburetor is too rich for such temperature conditions.

The principal object of this invention is to provide a valve attachment for use with the intake manifold which, while the engine is running, is closed, and which, when the engine is stopped, will provide vented openings to the atmosphere for the escape of the hot residual mixture in the intake manifold.

When the engine is in operation, the valve of this invention is closed by the intake suction in the manifold so that the engine operates in the usual way. When the engine is stopped, a spring-operated valve acts to open the valve to provide vent or escape openings for the residual hot mixture, thereby facilitating restarting of the engine, even if the manifold is still hot, due to the fact that this too-rich residual mixture has been released.

More particularly, the invention comprises a spring-pressed valve, the interior of which is open to the suction of the intake manifold, the suction serving to move the valve against the spring to close the valve by sealing off the apertures or vents in the normal operation of the car or truck. The spring acts when the engine stops, to open the valve to a position to clear or open the apertures so that the rich, hot mixture in the manifold will be released.

In a modification of the invention, the valve as above described is provided with electro-magnetic means for closing it, cooperating with the suction feature also serving to close the valve. The electromagnet is in circuit, with the ignition system of the car or truck, so that when the engine is operating, the magnet and suction close the valve.

In a second modification of the invention, the valve of this invention is provided with a mechanical device for closing it, cooperating with the suction feature also serving to close the valve. This mechanical device is operatively connected with the accelerator, so that when the accelerator is depressed as in normal running, the valve is closed.

Another feature of the invention is this:

If the engine has been operating for some time and all the parts are fairly hot, and the engine is stopped, it has been found that the mixture of fuel and air from the carburetor and from the intake manifold tends to back up and diffuse into

2

the air filter, particularly through the perforated pipe commonly present in air filters. This mixture is too rich for starting the motor again, especially if the parts are still hot, and another feature of this invention is to provide an attachment for the air filter which will allow the hot mixture which tends to accumulate in the air filter to pass outwardly therefrom, so that when the engine is started again, the mixture is not too rich.

In actual use of this invention, the spring-pressed valve which is closed by the suction in the intake manifold when the engine is operating, and opened by the spring when the engine is stopped, greatly improves the starting of the engine under the conditions stated. However, the use of the vent attachment for the air filter in cooperation with the valve mentioned still further improves the starting of the motor when it is fairly hot.

The valve of this invention and the vent in the air filter cooperate to remove the rich residual mixture from the manifold, carburetor and air cleaner. In some cases, cool air may enter the valve and move into the air filter and out the vent therein; in other cases, cool air may enter the air filter and its vent and pass out through the valve. In whatever direction these convection currents move, the residual too-rich mixture is cleared out from the manifold, carburetor and air cleaner.

The invention will now be described in connection with the accompanying drawings, wherein:

35 Fig. 1 is a side elevation of the valve of this invention, for mounting in the intake manifold.

Fig. 2 is a side view, partly in section, of the valve of Fig. 1 mounted in the intake manifold, the valve being open, and further showing the attachment for the air filter.

40 Fig. 3 is a vertical sectional view of the valve of Figs. 1 and 2, the valve being closed.

Fig. 4 is an enlarged side view of the air filter attachment.

45 Figs. 5 and 6 are vertical sectional views of modifications of the valve, with auxiliary electromagnetic and mechanical operating features, respectively.

50 Referring now to these drawings, the invention comprises a substantially cylindrical valve body indicated generally at 2, provided with external threads 4 adapted to be threaded into a corresponding threaded opening in the intake manifold 6 of an internal combustion engine. The valve body 2 is provided with a passage 8 opening into a larger chamber 10 providing a shoulder 12.

55 The valve body further includes a head 14 threadably engaged at 16 with the body. The valve body is provided with an inner annular valve seat 18, positioned a little below the underside of the head 14. The head 14 just above the

valve seat 18 is provided with a number of apertures or vents 20 opening into the atmosphere.

A disc valve 22 is adapted to be pressed upwardly by a spring 24, seated on the shoulder 12, the spring pressing the valve upwardly from its seat so that the apertures 20 will open to the atmosphere.

When the engine is in operation during normal running, the suction in the intake manifold pulls the valve 22 against the seat 18 to seal off the apertures 20. As soon as the engine stops, and there is no longer suction in the manifold, the spring 24 moves the disc valve 22 upwardly away from its seat to clear the apertures 20 so that the hot fuel mixture in the manifold passes upwardly through the valve and out of these apertures, thereby draining off the too-rich mixture. This too-rich mixture makes it difficult to start the engine if the parts are still fairly hot. But if this mixture is cleared out, as with the valve of this invention, the engine starts much more easily. When the engine starts again, the suction, of course, pulls down the valve 22 against its seat to seal off the apertures or vents 20.

The valve as just described greatly improves and facilitates the restarting of the engine while the parts are still hot. However, it has been found that when the engine is stopped and the parts are still hot, residual fuel-air mixture diffuses upwardly into the air filter, a conventional type of which is indicated at 30. The usual air filter is provided with a vertically positioned pipe 32 for delivering filtered air to the carburetor, diagrammatically shown at 34, this pipe usually being provided with apertures 36. When the engine is stopped, the hot fuel-air mixture tends to diffuse into the chamber 37 of the air filter, which mixture is too rich for subsequent restarting of the engine. In order to drain off this mixture, one wall of the air filter is provided with one or more escape openings 38 and a hood 40, provided with vents 41, positioned over these openings by means of bolts 42, the hood being provided with metallic wool or any suitable filtering material 44. When the engine stops, the hot, too-rich fuel-air mixture drains outwardly through the holes 38, and through the vents in the hood 40, thereby still further facilitating the restarting of the engine because of the removal of this too-rich mixture.

Referring now to the modification shown in Fig. 5, the valve there shown is provided with a spring pressed valve disc 22a and spring 24a as before. Mounted on top of the valve is a housing 50 in which is mounted a solenoid 52 in which is housed a plunger 54, which is non-metallic and provided with an iron head 56 acting as the armature. The plunger 54 rests on disc valve 22a. The solenoid 52 is connected by wire 58 in series with the low voltage part of the ignition circuit, the other end of the wire being grounded in the valve body.

In operating, suction closes the valve as before, when the engine is running, the closing being aided by the solenoid, the circuit of which is closed to move the armature down to close the valve. When the motor stops, the spring 24a raises the armature and valve and clears the apertures 20.

Referring to Fig. 6, the top 60 of the valve housing is provided with a plunger 61 which rests on valve 22b and is urged upwardly by a spring 62. The housing carried an angled bracket 64 provided with a bell-crank type of lever 66, which is pivotally connected to the top of plunger 61,

by pin 63 in a slot at the top of the plunger, one arm 68 of the lever being pivoted at 70 to the bracket 64, the other arm being connected through a spring 72 to the accelerator linkage 74.

In operation, suction closes the valve 22b when the engine is operating; when it stops, spring 62 lifts plunger 61 and spring 62 opens the valve as before.

The valve 2 in the intake manifold, by itself, greatly facilitates the starting of a hot engine, the hot mixture passing out through the valve. However, the operation is improved by convection currents of cool air coming in through the air filter and the apertures 38 therein, and out the valve. In other cases, cool air may enter the valve in the manifold and a convection current passes backwardly into the carburetor and out the air filter and the vents 38 therein. The direction of such convection currents depends on the temperature conditions. In any case, the starting of a hot engine is greatly facilitated.

The valve forming the subject matter of this invention may be mounted on the carburetor, instead of on the intake manifold near the carburetor, as shown. The carburetor would need to be designed to accommodate the attachment. When so mounted, it would act as before, in that when the engine stops, the valve opens as described to open the air vents 20 to the manifold adjacent the carburetor and allow the rich mixture therein to escape through vents 20, or cool air to enter and escape with the mixture through the vents 41 in the air filter.

The valve of this invention can also be used with two-cycle engines and where so used, the valve would be screwed onto and would open into the crankcase of such engine.

While the invention has been described in some detail, it should be understood that the invention is not to be limited to the exact details shown, but may be carried out in other ways.

I claim as my invention:

1. In combination with the intake manifold and an air filter of the type containing a pool of liquid of an internal combustion engine, a valve body positioned on the intake manifold and opening into it, said valve body being provided with apertures opening into the atmosphere, a spring pressed valve in said valve body, the suction in the manifold acting to move the valve against the spring to seal off said apertures when the engine is operating, said spring acting to move the valve to open the apertures when the engine stops, said air filter being provided with apertures located below the pool of liquid therein and opening into the atmosphere; said valve and said apertures in the air filter cooperating to set up convection currents of cool air through the manifold and air filter when the engine has stopped, for clearing residual fuel-air mixture from the manifold and air filter.

2. The combination as set forth in claim 1, further including an apertured-hood over said apertures in the air filter, and fibrous filtering material enclosed in said hood.

3. In combination, an air cleaner and filter for an internal combustion engine, said cleaner comprising a chamber in the upper part thereof provided with a mass of filamentary filtering material, and comprising a chamber in the lower part thereof, a vertically extending perforated pipe extending from the upper chamber through the lower chamber, one wall of said lower chamber being provided with escape apertures open to the atmosphere, for providing passages for

the escape of fuel-air mixture from said lower chamber, a valve carried by the intake manifold and having an escape passage therein, means cooperating into said valve for closing it by suction in the manifold when the engine is operating and opening it when the engine is stopped, the escape passage in said valve cooperating with said escape apertures in the wall of the lower chamber for allowing the escape of fuel-air mixture when the engine is stopped.

4. The combination as set forth in claim 3, further including a hood filled with porous filtering material positioned over said apertures.

5. A vacuum or suction operated valve, comprising a valve body adapted to be secured on the intake manifold of an internal combustion engine, said valve body being provided with gas escape apertures, a valve seat in said valve body and means, including an electromagnet, for moving said valve to the closed position to close said apertures during engine operation and for opening the valve to open said apertures when the engine is stopped.

6. A vacuum or suction operated valve, comprising a valve body adapted to be secured on the intake manifold of an internal combustion engine and opening into the manifold, said valve body being provided with apertures opening into the atmosphere, a spring pressed valve in said valve body, the suction in the manifold acting to move the valve against the spring to seal-off said apertures during engine operation, an electromagnet, including an armature cooperating with said suction effect, for moving said valve to, and holding it in closed position when the circuit is closed, the valve spring acting to move the armature in the opposite direction when the circuit is broken to open the valve.

7. A vacuum or suction operated valve, comprising a valve body adapted to be secured on the intake manifold of an internal combustion engine and opening into the manifold, said valve body being provided with apertures opening into the atmosphere, a spring pressed valve in said body, the suction in the manifold acting to move the valve against the spring to seal-off said apertures during engine operation, and lever means cooperating with said suction effect, for moving said valve to and holding it in closed position.

8. A vacuum or suction operated valve, comprising a valve body adapted to be secured on the intake manifold of an internal combustion engine and opening into the manifold, said valve body being provided with apertures opening into the atmosphere, a spring pressed valve in said valve body, the suction in the manifold acting to move the valve against the spring to seal-off said apertures during engine operation, and plunger and lever means, including a cooperating spring, cooperating with said valve, for moving the valve to the closed and open positions.

9. A vacuum or suction operated valve, comprising a valve body adapted to be secured on the intake manifold of an internal combustion engine, said valve body being provided with gas escape apertures, an annular valve seat in said body, and a spring pressed disk valve the spring of which is inside the valve body, said disk valve adapted to be moved by manifold suction against its spring to seal-off and close said gas escape openings during engine operation, said valve spring acting to move the disk valve to open said gas escape apertures when the engine is stopped.

10. A vacuum or suction operated valve, comprising a valve body adapted to be secured on the

intake manifold of an internal combustion engine, said valve body being provided with gas escape apertures, an annular valve seat in said body, a spring pressed disk valve the spring of which is inside the valve body, said disk valve adapted to be moved by manifold suction against its spring to seal-off and close said gas escape openings during engine operation, said valve spring acting to move the disk valve to open said gas escape apertures, and an electromagnet cooperating with said suction effect for moving said valve to, and holding it in closed position during engine operation.

11. A vacuum or suction operated valve, comprising a valve body adapted to be secured on the intake manifold of an internal combustion engine, said valve body being provided with gas escape apertures, an annular valve seat in said body, a spring pressed disk valve the spring of which is inside the valve body, said disk valve adapted to be moved by manifold suction against its spring to seal off and close said gas escape openings during engine operation, said valve spring acting to move the disk valve to open said gas escape apertures, and lever means, cooperating with said suction effect, for moving said valve to, and holding it in closed position.

12. A vacuum or suction operated valve, comprising a valve body adapted to be secured on the intake manifold of an internal combustion engine, said valve body being provided with gas escape apertures, an annular valve seat in said body, a spring pressed disk valve the spring of which is inside the valve body, said disk valve adapted to be moved by manifold suction against its spring to seal-off and close said gas escape openings during engine operation, said valve spring acting to move the disk valve to open said gas escape apertures, and spring operated plunger and lever means, cooperating with said valve, for moving it to the closed and open positions.

13. A suction operated valve adapted for use on the intake manifold of an internal combustion engine, comprising a valve body having a passage therein adapted to communicate with the interior of the manifold, provided with a gas escape aperture opening to the atmosphere, a valve seat in said valve body, and a valve in said valve body, movable by suction in the manifold to seat on said valve seat to close off said gas escape aperture when the engine is operating, and to open said passage to the atmosphere when the engine is stopped.

14. A suction operated valve adapted for use on the intake manifold of an internal combustion engine, comprising a valve body having a passage therein opening into the intake manifold, a valve seat in said valve body, a valve adapted to fit onto said valve seat to close said passage, and a spring for moving said valve to the open position, whereby the valve is completely closed by suction when the engine is operating and is held completely open by said spring when the engine is stopped.
